UNITED STATES PATENT OFFICE

MORTON HAGUE, OF CHICAGO, ILLINOIS

SHRINE

Application filed June 15, 1932. Serial No. 617,401.

This invention relates to an improved shrine such as is used in connection with certain religious rites.

The main object of the invention is to provide a shrine of the type referred to which is adapted for use in the home or in places where an altar or shrine in a church is not readily available.

Another object of the invention is to provide a shrine of the class described which may be of small and compact size so that it may constitute not only an article of utility but also an article in the nature of an ornamental statue or plaque which may be attractively displayed in the home or other places.

Still another object of the invention is to provide a shrine which will be useful, not only in the usual daily devotional rites but also in connection with the administering of certain religious rites.

Other objects and advantages of the invention will be understood by reference to the following specification and accompanying drawing in which is illustrated a shrine embodying a selected form of the invention.

In the drawing:—

Fig. 1 is a plan.

Fig. 2 is a front elevation.

Fig. 3 is a section on the line 3—3 of Fig. 1.

Figs. 4, 5 and 6 are perspectives of certain parts used in connection with the shrine illustrated in Figs. 1 to 3, inclusive.

Referring now to the drawing, the shrine therein illustrated includes a base 10 and a panel 11 which extends upwardly from the rear edge of the base. The base and panel are preferably molded of any suitable material which is light in weight when finished; for example, plaster or plaster composition which is quite porous when hard and dry.

In simulation of the approach to an altar, the base is provided with steps such as indicated at 12 and a recess 13 is formed in the base for positioning a vigil light which usually consists of a ruby colored glass 14 within which is disposed a candle 15. Immediately in front of the vigil light holding recess 13, the base is provided with a forward projection 16 which is recessed to form a font 17.

The font 17 concludes an impervious shell 18 which may be of celluloid or other suitable material.

To exemplify the attitude of devotion or worship, a pair of statuettes 19—19 in the form of angels are mounted on the base, one on each side of the vigil light 14.

The panel 11, on its front face, is provided with a frame-like, forwardly projecting rib 20 which serves to give prominence to a pictorial representation 21 of any one of a series of subjects of devotion which may be mounted on the panel. The pictures 21 are preferably provided with a heavy cardboard backing 22 which is slotted so as to permit the bending out therefrom of rearwardly projecting, spaced tongues 23. The tongues 23 are adapted to frictionally fit in an opening 24 provided in the panel 11 and said tongues thereby serve to removably mount the picture on the panel.

The panel 11 is also provided with a receptacle 25 which preferably opens to the back of the panel and this receptacle serves as storage space for a sick call outfit designated in its entirety 26. The sick call outfit includes several items which are used in administering last rites and need not be particularly explained in this application. However, it may be said that the sick call outfit is enclosed in a suitable box or the like such as indicated and that it includes a crucifix 27 such as shown in Fig. 4 and a pair of wax candles of small diameter but considerable length, substantially of proportions such as depicted in Fig. 6.

The crucifix in the sick call outfit furnished with the described shrine will be provided with a spring device, for example a pair of spring tongues 28 which may be inserted in the opening 24 in the panel to mount the crucifix on the panel in place of one of the pictorial representations such as 21. In connection with the display of the crucifix on the panel, the candles such as shown in Fig. 6 are to be positioned adjacent the opposite sides of the crucifix. For so positioning the candles, the statuettes 19 are each provided with a candle holder recess 29 which is adapted to receive and support one of the candles.

referred to. So as to render the candle holder recesses 29 substantially invisible or inconspicuous, the wings 30 of each statuette diverge somewhat so as to provide a depression 31 between the wing and in which depression the candle holder recesses 29 are located. By inspection of Fig. 2, it will be observed that the candle holder recesses 29 will not be openly visible from normal view-
10 points.

For the purpose of hanging the shrine on a wall, it is provided with a pair of eyelets 32 which are suitably anchored to the back of the panel. Suitable cushion buttons 33 are
15 provided for maintaining the panel spaced outwardly from the wall the same distance at its lower edge as at its upper edge where the eyes 32 and the hooks engaged thereby hold the panel spaced from the wall. Suitable
20 means such as a latch 34, pivotally mounted on a screw or the like 35 may be provided on the back of the panel for maintaining the sick call outfit 26 in the recess 25.

Changes in the described construction and
25 arrangement may be made without departing from the spirit of the invention, the scope of which should be determined by reference to the following claims, the same being construed as broadly as possible consistent with
30 the state of the art.

I claim as my invention:—

1. In a shrine of the class described, the combination of a base, and a pair of statuettes of angels in relatively spaced relation on said base, said statuettes each having diverging wings and each being provided with candle holder recesses intermediate its wings.

2. In a shrine of the class described, the combination of a base, and a pair of statuettes of angels in relatively spaced relation on said base, said statuettes each having diverging wings having a depression therebetween and each being provided with candle holder recesses in said depression between the wings.

3. In a shrine of the class described, the combination of a base, an upright panel, a representation of a subject of devotion, means for removably mounting said representation on the panel whereby a series of representations may be interchangeably mounted on said panel, a vigil light holder in said base, and a pair of statuettes of angels on said base on opposite sides of said vigil light holder, said statuettes each having diverging wings having a depression therebetween and each being provided with a candle holder recess in the depression between the wings.

4. In a shrine of the class described, the combination of a base, a panel extending upwardly from the base at its rear, said base and panel being molded of material which is porous when hardened, a vigil light holder in the base and a font having an impervious lining shell in the base in front of the vigil light holder, said panel being provided with

means for positioning thereon a representation of a subject of devotion.

5. In a shrine of the class described, the combination of a base and a panel extending upwardly therefrom, said base and panel being furnished with representations and articles for religious rites, and said panel being provided with a receptacle for receiving a sick-call outfit substantially as described.

6. In a shrine of the class described, the combination of a base and a panel extending upwardly therefrom, said base and panel being furnished with representations and articles for religious rites, said panel being provided with a receptacle for receiving a sick-call outfit substantially as described, and means for maintaining such outfit in said receptacle.

7. In a shrine of the class described, a panel having an opening therein, a representation of a devotional subject comprising a picture having a cardboard backing, and means for removably mounting the picture on said panel comprising a tongue formed integral with and projecting rearwardly from said backing within the area of the picture, said tongue fitting in said panel opening to frictionally maintain the picture in place on the panel.
